COMBINED EGG CUP AND SALT CELLAR

Fred Snyder, 53 W. 23rd St.,
New York, N.Y. 10010

Filed Dec. 6, 1971, Ser. No. 205,452

Term of patent 14 years

Int. Cl. D7—01

U.S. Cl. D7—5

Fig. 1

Fig. 2

Fig. 3

Fig. 4

Fig. 5

Fig. 6

FIG. 1 is a side elevational view of a combined egg cup and salt cellar, showing my new design;

FIG. 2 is a front elevational view thereof;

FIG. 3 is a rear elevational view thereof;

FIG. 4 is a top plan view thereof;

FIG. 5 is a bottom plan view thereof; and

FIG. 6 is a top plan view thereof, the salt cellar having been removed for convenience of illustration.

I claim:

The ornamental design for a combined egg cup and salt cellar, substantially as shown and described.
